HUMIDIFYING APPARATUS

Frederick D. Potter, Linden, N. J.

Application April 9, 1936, Serial No. 73,412

3 Claims. (Cl. 126—350)

My invention relates to humidifying apparatus for use in a building having a heating appliance with a pipe for smoke and products of combustion sufficiently hot to serve for converting water into vapor or steam.

The object of the invention is to provide new and useful, simple, inexpensive, and readily operated means for humidifying the air of a room or rooms of a building.

10 Fig. 1 of my drawing is an elevational view, partly in section, of a preferred form of apparatus embodying my invention; and

Fig. 2 is a sectional detail view.

Reference character 10 designates a water supply tank supported at a level above the source of heat, as for example supported near the ceiling of a basement containing a heating furnace equipped with a so-called smoke pipe 12 for outlet of smoke and products of combustion and 20 serving as my source of heat for room humidifying purposes.

Tank 10 may conveniently be equipped with a sight tube 14 to enable the height of water therein to be readily observed.

25 The outlet pipe 16 from tank 10 leads to vessel 18 which is open or at least vented at its top.

The supply of water from tank 10 to vessel 18 is automatically regulated by the end of pipe 16 being submerged in the water in vessel 18, so 30 that water is supplied from tank 10 to vessel 18 only as the water in vessel 18 is used up.

Vessel 18 has a low-down outlet pipe 20 leading to water heating means located in the smoke pipe 12.

35 In the form shown, the water heating means is made up of pipe and pipe fittings, and comprises a longitudinal pipe 21 and cross head pipes 22 and 24. The heating means is preferably so arranged that the parts thereof can be removably and 40 replaceably assembled in connection with a single length or section of smoke-pipe, as 12a.

As shown, smoke-pipe section 12a has a pair of slots 12b, 12b, in one end, and a pair of slots 12c, 12c, in its opposite end.

45 With this arrangement the cross-pipe member 22 can be assembled with the longitudinal member 21 and these inserted in the smoke-pipe section 12a, with the cross member 22 received in slots 12b, 12b.

50 The parts of cross head member 24 can then be inserted through slots 12a, 12c, and screwed into the T 26 on longitudinal pipe member 21.

Such arrangement leaves the cross pipe members 22, 24, projecting through the smoke-pipe 55 12a, and capped at one end as indicated at 28, and

with the other ends open and likewise projecting through and beyond the smoke-pipe section 12a.

The water supply pipe 20 can be connected as by a union 30 with one cross member, as 22, and the other cross member 24 connected, as by 5 union 32, to a pipe, as 34, for supplying steam or water vapor to the room or building having need for air humidification. In the case of a residence with a basement furnace and furnace smoke-pipe, the pipe 34 may pass immediately or with 10 branches to the room or rooms on the floor or floors above. When the smoke-pipe is to be taken down in the summer season, the unions can be opened up and the pipe sections taken apart without interference therewith by the humidifier heating device.

Tank 10 has a vent near its top provided with 15 vent valve 40. As shown, the water supply pipe 42 is connected to the outlet pipe 16 at a point between outlet valve 44 and the tank 10, and the 20 water supply pipe 42 is provided with a valve 46.

When the water supply gets low, which with, say, an 80 or 100 gallon storage tank 10 will be 25 not until after several days' use, vent valve 40 is opened, outlet valve 44 closed, and supply valve 46 opened, and each of these operations is reversed when the water rises to a level sufficiently high in tank 10. The outlet valve 44 can be used to regulate the degree of humidification by 30 regulating the feed of water to vessel 18, and additional means of regulation may be provided, as, for example, a valve 48 provided in the pipe 20 leading from vessel 18 to the heating device 21, 22, 24. The smoke-pipe section 12a is preferably 35 so disposed that the parts 21, 22 and 24 of the heating device are all substantially level, and the pipe 16 is so disposed that the level of water in the vessel 18 is at about the same height as the heating device. In this way water is supplied as 40 it is vaporized but no head of water can remain above the heating device in the vapor exit pipe.

It will be seen that apparatus in accordance with my invention can be readily and inexpensively constructed and is free from need of attention over long intervals, cannot readily get 45 out of order, there is no possibility of explosion or of getting hot water instead of steam or vapor from the pipe leading to the room or building.

I claim:

1. In a humidifying apparatus, a smoke-pipe section of a furnace or the like, slots provided in the opposite ends of said section, a vaporizer comprising pipe and fittings received and supported in said slots, and water supply means and 55

water vapor delivery means respectively connected to said vaporizer.

2. In a humidifying apparatus as claimed in claim 1, in which the vaporizer and water supply means are disposed in substantially the same level plane.

3. In humidifying apparatus the combination of a smoke-pipe, a water vaporizer therein, means

for passing water vapor from one end of said vaporizer, and means for automatically supplying compensating water to said vaporizer as the same is converted to water vapor and delivered in such state, said water supply means having means for maintaining the water level therein in substantially the same level plane as the vaporizer. 5

FREDERICK D. POTTER.
